UNITED STATES PATENT OFFICE.

PERCY ELMER KRIEBEL, OF ATLANTIC CITY, NEW JERSEY, ASSIGNOR TO AMERICAN ENGINEERING COMPANY, OF PHILADELPHIA, PENNSYLVANIA, A CORPORATION OF PENNSYLVANIA.

ELECTROHYDRAULIC STEERING GEAR.

Application filed April 15, 1924. Serial No. 706,710.

To all whom it may concern:

Be it known that I, PERCY ELMER KRIEBEL, a citizen of the United States, residing in Atlantic City, Atlantic County, New Jersey, have invented an Electrohydraulic Steering Gear, of which the following is a specification.

My invention relates to controlling apparatus and it has particular relation to electro-hydraulic steering systems.

One object of my invention is to provide a hydraulic motor of novel construction which is characterized by the absence of side-thrust guides, blocks, slippers and connecting links.

Another object of my invention is to provide an electro-hydraulic steering system which is capable of installation in restricted spaces by reason of its compactness and general simplicity of design.

A further object of my invention is to provide a special form of connection between the hydraulic motor and the actuating pump which is so designed as to avoid leakage upon the operation of the hydraulic motor.

According to my invention, I provide a hydraulic motor, which comprises a pair of rams and a pair of swiveled cylinders for said rams, the former being secured to the respective ends of a rudder-crosshead. The cylinders are operatively connected by means of flexible piping with a reversible, variable-stroke pump which may be driven by a continuously running electric motor. The hydraulic system may be maintained solid by means of a shuttle-valve which is operatively associated with the cylinders and a supply tank. Follow-up means is also provided for returning the reversing element of the variable-stroke pump to its neutral position when the rudder has moved through a desired angle.

With these and other objects and applications in mind, my invention further consists in the details of construction and operation and arrangement hereinafter described and claimed and illustrated in the accompanying drawings, wherein—

Fig. 1 is a top plan view of an electro-hydraulic steering gear embodying my invention;

Fig. 2 is a side elevational view of the structure of Fig. 1; and

Fig. 3 is a detail sectional view of the shuttle-valve.

In the illustrated form of embodiment of my invention shown in the drawings, a pair of hydraulic motors 1 and 2 comprising cylinders 3 and 4 and rams 5 and 6, respectively, are swivelly mounted by providing the former with upper and lower trunnions 7-7 and 8-8, respectively. A bed-plate 9 is provided with pockets 10 for the reception of the lower trunnions 8-8, while the upper pair of trunnions 7-7 are journaled in bearings formed in a tie-piece 11. The outer ends of the rams 5 and 6 are pivotally secured to the respective ends of a rudder-crosshead 12 or other rotary or oscillatory structure by means of pins 13 and 14, respectively, each pin being removably secured to the ram by means of a set screw 15.

An actuating fluid, say oil, may be supplied to one cylinder and substantially simultaneously withdrawn from the other cylinder by means of a reversible, variable-stroke pump 17 through pipes 18 and 19, respectively. The outer ends of the pipes 18 and 19 are secured to cylinder openings 21 and 22 by means of clips 23 and 24 of usual design, respectively. In order to avoid the loosening of the connection between the outer ends of the pipes 18 and 19 and the cylinder clips 23 and 24 as the cylinders 3 and 4 are oscillated, I provide curved or coiled portions 26 and 27 immediately adjacent to the cylinder connection, so that the force incident to the turning movement of the fixed outer ends of the pipes 18 and 19 are absorbed by the spring of the curved coil portions 26 and 27, respectively.

The reversible, variable-stroke pump 17 may be of the type, for instance, which is described in the patent to Hele-Shaw and Martineau, No. 1,077,979, dated Nov. 11, 1913. A pump of such type is provided with a control element (not shown) for determining the quantity as well as the direction of flow of the fluid through the flexible pipes 18 and 19,—the arrangement being such that when the control element (not shown) is moved in one direction from a neutral position, say to the left, fluid is delivered under

pressure through the pipe 18 to the cylinder 3 while fluid is substantially simultaneously drawn from the cylinder 4 into the pump 17 through the pipe 19. However, when said control element is moved to the right from a neutral position, fluid is delivered through the pipe 19 to the cylinder 4 and substantially simultaneously withdrawn from the cylinder 3 through the pipe 18, the neutral position of the control element representing that position, where there is no flow through either of the pipes 18 or 19. The pump 17 may be actuated by means of an electrical motor 28 of the continuously running type, or other power source, as, for instance, a steam turbine, through a flexible coupling 29.

The control element (not shown) for the pump 17 is secured to a control-rod 31 slidably mounted in spaced supporting pedestals 32 and 33, the latter also providing a revoluble mounting for a control drum 34. The control drum 34 is operatively associated with a corresponding drum in the control station of the ship by means of a flexible wire rope (not shown). The drum 34 constitutes a nut for a threaded shaft 35 which is mounted for longitudinal movement in the pedestals 32 and 33. A floating lever 36 is pivotally mounted midway its ends on the outer end of the longitudinally movable control-rod 31. One end of the floating lever 36 has a sliding-block connection 37 with the end of the threaded shaft 35, while the other end thereof is connected through a link 38 with a pivot pin 39 mounted on an adjacent outer end of the rudder-crosshead 12.

When the control drum 34 is actuated in accordance with the movement of the operating driving drum in the pilot house of the ship (not shown), the threaded shaft 35 is moved from the neutral position shown in the drawing to the left. Since the rudder-crosshead 12 is not in motion at this time, the cross head pin 39 is a fixed point about which the floating lever 36 and the link 38 are swung, under the force of the outwardly moving threaded shaft 35. The resulting outward movement of the floating lever 36 causes a corresponding outward movement of the pump control rod 31, thereby actuating the control element (not shown) of the reversible variable stroke pump 17 from its neutral position to an operating position, permitting the pump 17 to supply fluid under pressure through the pipe 18 to the cylinder 3 while simultaneously withdrawing the liquid from the cylinder 4 through the pipe 19, the gradual filling of one cylinder and the discharge from the other being substantially equal. The outward movement of the ram 5 and the inward movement of the ram 6 continues so long as the drum 34 is rotated and the

pump control element (not shown) is held out of its neutral position by the slidable control-rod 31.

The swinging movement of the cylinders 3 and 4, incident to the movement of the rudder-crosshead 12, is prevented from loosening the connection between the ends of the supply pipes 18 and 19 and their respective cylinders by reason of the flexible arrangement of the pipes 18 and 19, particularly the coiled portions 27 and 26 thereof.

When it is desired to stop the movement of the rudder-crosshead 12, the rotation of the drum 34 is discontinued which results in the sliding-block connection 37 becoming a fixed point for the linkage 36 and 38, rather than the pin 39. Inasmuch as the pump 17 is still delivering fluid under pressure to the cylinder 3, causing the continued turning of the rudder-crosshead 12, the motion of the latter through the linkage 38 and 36 actuates the slidable control rod 31 inwardly until the reversing element (not shown) of the pump 17 is moved from its operating position to its neutral position, whereupon the pump 17 becomes inoperative and the rudder-crosshead 12 is brought to rest.

As may readily be seen, a further movement of the control rod 31 by the drum 34 into its reverse position causes a reverse movement of the rudder-crosshead 12, such movement continuing until the drum 34 is brought to rest, whereupon the linkage 38 and 36 operates to return the pump control element (not shown) to its neutral position.

While the fluid system, which includes the pump 17, the pipes 18 and 19 and the cylinders 3 and 4, when once filled, is theoretically solid for all time, leakages, for instance, due to slight mechanical differences in the cylinder displacement, require an automatic replenishment from time to time. To this end, I provide a three-way surge valve 41 of usual design, as shown in Fig. 3. This valve comprises a cylindrical casing 42 having a central chamber 43, which is connected by a pipe 44 to a supply tank 45 formed in the bed-plate 9, and it also comprises end-chambers 46 and 47. The end chamber 46 is connected by means of pipes 48 and 49 with one side of the pump 17 while the other end chamber 47 is connected by pipes 51 and 52 with the other side of the pump 17.

The chambers 43-46 and 43-47 are separated by a pair of inwardly extending annular flanges 53 and 54, respectively. The flanges 53 and 54 constitute valve seats for a longitudinally slidable spindle 55 having grooves 56 extending lengthwise thereof. The spindle 55 is further provided with valve disks 57 and 58 on the ends thereof, which are so constructed with relation to the other parts of the valve, that when the

spindle 55 is in one extreme position it permits communication from the end chamber 47 to the central chamber 43 through the grooves 56, while communication is cut off 5 between the other end chamber 46 and the central chamber 43. When the spindle 55 is in the other extreme position, communication is established between the end chamber 46 and the central chamber 43 through 10 the groove 56, while communication between the end chamber 47 and the central chamber 43 is simultaneously interrupted.

With the above-described arrangement of 15 valve parts and assuming the pump 17 discharging fluid under pressure into the cylinder 4, the pressure created in the end valve chamber 47 by reason of its connection through the pipes 51 and 52 with pressure 20 side of the pump 17 is such that the valve disk 58 is moved into engagement with the annular flange 54 to interrupt the connection between the end valve chamber 47 and the central valve chamber 43. As previously 25 pointed out, the resulting movement of the valve spindle 55 actuates the valve disk 57 out of engagement with the annular flange 53, establishing a connection between the central chamber 43 and the end chamber 46. 30 Since the end chamber 46 is connected through the pipes 48 and 49 with the suction side of the hydraulic system, that is, the side of the pump 17 receiving fluid from the cylinder 3, and since the central chamber 43 35 is directly connected to the supply tank 45, the pump 17 may take up from the supply tank 45 a sufficient quantity of fluid to keep the hydraulic system solid. The connection between the suction side of the hydraulic 40 system and the supply tank 45 permits the excess discharge from the cylinder 3 to drain back into the supply tank 45 which, however, can be immediately recovered upon the 45 operation of the other cylinder.

Should it become necessary to operate the rudder-crosshead 12 by means of the usual hand mechanism, I provide means whereby the fluid in the hydraulic system may freely circulate from one cylinder to the other, said 50 means comprising a valve-controlled pipe 58 which is connected, respectively, to the pipes 49 and 52. The opening of the valve 59 in the pipe 58 permits the fluid, which is forced out of one cylinder into the other, to pass 55 freely around the pump 17 through the pipes 49, 58 and 52.

While I have shown only one form of embodiment of my invention, for the purpose of describing the same and illustrating its 60 principles of construction and operation, it is apparent that various changes and modifications may be made therein without departing from the spirit and scope of my invention. I desire, therefore, that only such 65 limitations shall be imposed thereon as are

indicated in the appended claims or as are demanded by the prior art.

I claim:

1. A steering mechanism including a hydraulic motor, one element of which is swiv- 70 eled.

2. In combination, a swiveled hydraulic motor, and a variable-stroke pump for operating said motor.

3. In combination, a swiveled hydraulic 75 motor, a variable-stroke pump, and a pipe operatively associating said pump and motor, said pipe having a flexible portion immediately adjacent to said motor.

4. In combination, a movable element, a swiveled motor for actuating the same, a pump for operating said motor, and a continuously running electric motor for driving said pump.

5. In combination, a movable element, a swiveled motor for actuating the same, a pump for operating said motor, flexible means for operatively associating said pump and said motor, and a continuously running 85 electric motor for driving said pump. 90

6. In combination, a movable element, a swiveled motor for actuating the same, a variable-stroke pump, flexible means for operatively associating said pump and said swiveled motor, and a continuously running 95 electric motor for driving said pump.

7. In combination, a movable element, a pivoted cylinder, a ram extending from said cylinder and operatively associated with said element, a variable capacity pump, and flexible means for conducting the actuating fluid from said pump to said pivoted cylinder.

8. In combination, a crosshead, a pair of swiveled hydraulic motors for actuating the respective ends of said crosshead, and a variable-stroke pump for operating said motors.

9. In combination, a crosshead, a pair of swiveled hydraulic motors for actuating the respective ends of said crosshead, a reversible variable-stroke pump, and flexible pipes for operatively associating said pump and 105 motors.

10. In combination, a crosshead, a pair of swiveled cylinders, rams for said cylinders operatively associated with the respective ends of said crosshead, a variable-stroke pump for operating said motors, and flexible piping for operatively associating said pump and said cylinders.

11. In a hydraulic steering system, a rudder-crosshead, a pair of swiveled cylinders, rams for said cylinders secured respectively to the ends of said crosshead, a variable-stroke pump, and flexible piping for operatively associating said pump and said cylinders.

12. In a hydraulic steering system, the combination with a rudder-crosshead, of a pair of swiveled cylinders, rams for said cylinders secured respectively to the ends of 130

said crosshead, a reversible variable-stroke pump, flexible piping for operatively associating said pump and said cylinders, and a continuously operating motor for driving said pump.

13. In combination, a pair of cylinders provided with trunnions, a bed-plate providing bearings for certain of said trunnions, a tie-piece providing bearings for the remaining trunnions, rams extending from said cylinders, a rudder crosshead secured to said rams, and means operative to supply an actuating fluid to one of said cylinders.

14. In combination, a pair of cylinders provided with trunnions, a bed-plate providing bearings for certain of said trunnions, a tie-piece providing bearings for the remaining trunnions, rams extending from said cylinders, a rudder-crosshead secured to said rams, and means for supplying an actuating fluid to one of said cylinders and for simultaneously receiving the discharge from the other of said cylinders.

15. A hydraulic steering system comprising a rudder-crosshead, a pair of swiveled hydraulic motors operatively associated with said rudder-crosshead, a pump for supplying an actuating fluid to one of said hydraulic motors and for receiving at least a portion of the discharge from the other of said motors, a supply tank, a shuttle valve operable to permit the remaining portion of said discharge to pass into said supply tank, and means for driving said pump.

16. In a hydraulic system of steering, the combination with a rudder-crosshead, of a pair of swiveled hydraulic motors, the ram elements of which are respectively secured to the ends of said crosshead, a variable-

stroke pump having a control element for reversing the direction of operation thereof, flexible pipes extending from said motors to said pump, whereby fluid may be supplied to one motor and substantially simultaneously withdrawn from the other motor, means for controlling at will the position of said pump control element, and follow-up means actuated by said rudder-crosshead for returning said pump control element from an operating position to a neutral position.

17. In combination, a rudder-stock provided with a crosshead, a pair of swiveled cylinders, rams extending from said cylinders and respectively secured to the ends of said rudder-crosshead, a reversible variable-stroke pump, flexible piping for operatively associating said reversible pump and said cylinders, whereby actuating fluid may be supplied to one cylinder and removed from the other, a supply tank, a shuttle-valve having an operative connection with each of said cylinders and said supply tank, whereby the excess discharge from one of said cylinders may be by-passed to said supply tank and also permitting the pump to take up such amounts of fluid as are necessary to keep the system solid, a control element for varying the direction of operation of said pump, operating means for moving said control element from a neutral position to forward or reverse positions, and follow-up mechanism actuated by said rudder-crosshead for returning the pump control element from either of its forward or reverse positions to its neutral position.

PERCY ELMER KRIEBEL.
